METHOD OF FORMING INTEGRAL FINS
ON TUBING.Walter P. Hill, Detroit, Mich., assignor to Calumet
and Hecla Consolidated Copper Company,
Calumet, Mich., a corporation of Michigan

Application October 1, 1945, Serial No. 619,712

5 Claims. (Cl. 80—13)

1

The invention relates to finned tubing of that type in which the fins are developed from a portion of the material forming the wall of a plain tube. In the present state of the art, one method which has been extensively employed for forming such finned tubing is, first, to circumferentially score or groove the outer surface portion of the tube and to then axially compress the material between adjacent convolutions of said groove to develop therefrom radially projecting fins. Such operations are usually performed by rollers distributed about the tube in rolling intersecting relation thereto, each roller having a series of spaced disc portions which are progressively increased in width with a corresponding decrease in the width of the space between the same and the next adjacent disc. The axes of the rollers are at a slight angle to the axis of the tube and will thus develop a helical fin of progressively increasing diameter and decreasing thickness. This is due to the combined radially inward and axial pressures exerted by the successive discs. Other methods more or less analogous to the one just described have also been used for forming finned tubing but, in all, the fins during their development are subjected to axial compression as well as radial extrusion.

Finned tubes formed by the above methods are generally of a very poor structure and of uneven texture. This is due to the extreme cold working of the material, particularly on the opposite sides of each fin which tend to harden and embrittle the surface portions while leaving the center or core much softer. Also, the periphery of the fin has cracks formed therein which later may extend inward and destroy the tube. Consequently, the height of the fin is limited and the material of which the tube is formed must be of limited hardness.

Where finned tubes are used in heat exchange apparatus, it is desirable to have an unfinned portion at one or both ends of each tube which is of a diameter at least as great as that of the fins. This facilitates assembly of the structure and the insertion of the finned tubes through apertures in one wall of the casing which will fit the unfinned end portions. It is also desirable that these unfinned end portions should be of a wall thickness at least as great and preferably greater than the wall thickness of the finned portion of the tube. With methods heretofore used for finning tubing, it has been difficult to produce a structure such as just described for the original external diameter of the tube which is to be finned is generally less than the outer

5 diameter of the developed fins. It is possible to expand the end of the tube to a diameter equal to that of the fins but such operation results in reducing the wall thickness of the tube.

Among the objects of the instant invention are, first, the obtaining of a finned tube in which the fins are of a more uniform texture and comparatively free from defects common in structures of the type as heretofore made; second, the obtaining of a finned tube in which each fin is developed by radially inwardly directed pressure applied to the tube wall adjacent to opposite sides of the root of said fin; third, the obtaining of a finned tube in which each fin is developed solely from material extruded radially outward from the wall of the tube through the root of said fin; fourth, the obtaining of a finned tube in which each fin during its development is confined between axially spaced radially extending surfaces which fashion it to the desired cross sectional contour; fifth, the obtaining of a finned tube in which the surface portions are relatively free from work hardening and only slightly harder than the core portion between the same; sixth, the obtaining of a finned tube having unfinned portions which may be of greater diameter and greater wall thickness than the finned portions, and in a condition or temper permitting further cold working of the metal; and, seventh, the obtaining of a finned tube having wall portions tapering in thickness and/or diameter from a heavy end to the finned portion.

35 A further object of the invention is to obtain a method for forming the structures as above described more expeditiously and with greater accuracy than by methods heretofore used.

The invention, therefore, consists in the provision of a new type of finned tubing together with devices for producing the same as hereinafter set forth.

In the drawings:

Fig. 1 is an end elevation partly in section of a machine for carrying out my improved method;

Fig. 2 is a vertical central longitudinal section therethrough;

Fig. 3 is a longitudinal section through one of the forming rolls shown in Figures 1 and 2, and showing the roll in operative engagement with a tube being finned;

Fig. 4 is a fragmentary sectional view through a modified construction of forming roll; and

Fig. 5 is an elevation showing a finned tube in which the diameter of the fins is considerably greater than the diameter of the original tube.

The most characteristic feature of my improved

method for finning tubing is the elimination of axial compression of the fin during the development of the same. To accomplish this the pressure which may be applied to the tube by one or more forming rolls is directed substantially radially inward and has no component directed axially towards the fin during its development. However, this radially inward pressure will produce a displacement of material which can flow substantially only in an axial direction while beneath the displacing surface but will be extruded radially outward at a point beyond said surface. Such extrusion is due to the combination of the axially directed pressure on the displaced material and the reaction of the body of the tube against elongation thereof resulting in radial outward deflection. If the tube is confined so as to permit extrusion only through the root of the fin, then the entire fin will be developed from radially outwardly directed extruded material. In order, however, to fashion the fin to the desired cross sectional contour, the extruded material must be confined between axially spaced surfaces of corresponding contour. As these surfaces are in fixed relation to each other, they cannot axially compress the material therebetween but only direct it radially.

I have diagrammatically illustrated one form of the apparatus for producing finned tubing and more specifically for forming improved helical fins thereon. As shown in Figs. 1 and 2, A is a suitable frame including a pair of spaced parallelly arranged heads B and B' having bearings therein for rocker members C, C' and C² extending therebetween and equispaced from each other. Each of these rocker members has eccentrically journaled therein an arbor D for carrying a forming roll E. The rocker members are connected to each other through the medium of radially outwardly extending arms C³ and connected links C⁴ so that when one of said members is rocked a similar rocking movement will be imparted to each of the others. Thus, the arbors D and rolls E may be simultaneously moved radially towards or from a central axis therebetween which is the axis of the tube to be finned. Each of the rolls E has a series of annular peripheral portions E', E², E³, E⁴, E⁵ separated from each other by grooves F, F', F², F³, which are slightly tapered in an inward direction. The portion E' is substantially V-shaped in cross section with a radius curve at its outer end and is adapted to press a groove in the outer portion of the tube wall which extends helically thereabout (as hereinafter described). The portion E², E³ and E⁴ have their peripheral surfaces substantially straight in an axial direction but at a slight angle to the axis of the work. These surfaces are also progressively slightly increased in width axially with a corresponding progressive decrease in the width of the grooves therebetween. The portion E⁵ has a peripheral face of still greater width which is parallel to the axis of the tube. It is to be understood that the axis of the rolls and the arbors carrying the same are at an angle to the axis of the work tube so that the portions E', E², etc. are at the desired helix angle. Thus, while rolling about the work tube in intersecting contact therewith, the portion E' will advance said tube axially and the portions E², E³, E⁴ and E⁵ will successively traverse substantially the same helical path radially inwardly depressing the outer portion of the wall of the tube. The face of the portion E' adjacent to the groove F is substantially perpendicular to the axis of the work

tube and will, therefore, compel the axial advancement of said tubing and resist any stress tending to move the same in the opposite direction. The material displaced by the portions E², E³ and E⁴ will be forced to flow axially therebelow until in registration with the grooves which permit radial outward extrusion into said grooves. However, as these portions are progressively slightly increased in width, they will overlap portions of the tube wall not previously depressed and will force these radially inward. Thus, the width of the final groove F³ and the extruded material therein will be less than that of the first groove but the pressure exerted on the material during its displacement will always be radially inwardly directed without exerting any axial compression of the extruded material in the groove. The work tube G while operated upon by the rolls is supported by a mandrel I which extends beneath the portions E', E², E³, E⁴ and E⁵. This mandrel is anchored at a remote point (not shown) and is of sufficient length to receive the tube which is operated upon. However, at the operating point both mandrel and tube are floating with respect to the rolls engaging the same. The finned tube resulting from this process will have the fins thereof of substantially uniform texture and substantially free from work hardening on the surface portions thereof. Also, the peripheral edge of the fin will be convex in cross sectional contour, whereas the peripheral contour of the tips of fins produced by axial compression is concave and is subject to the development of cracks which may extend inward to the tube. Thus, the physical characteristics of the product are greatly improved.

If it is desired to produce a finned tube having an unfinned end portion of at least as great a diameter as the peripheral diameter of the fins, the original tube is preferably of this larger diameter. The rolls E are then provided with conical portions E⁶ which, first, come in contact with the tube while it is axially advanced and will reduce its diameter in advance of contact with the roll portion E'. Each of the succeeding portions will perform a further reduction in the diameter of the tube until limited by the mandrel I. The material displaced in this progressive decrease in diameter of the tube will be forced axially so that the portion of the tube on which the fins are developed will be increased in length. There will also be a change in helix angle in the rolling of the tube by the last section E⁵, the peripheral face of which is parallel to the axis of the tube so that the inwardly displaced material will elongate the tube between adjacent convolutions of the fin. In the completed structure the wall thickness of the finned portion of the tube will be considerably reduced over that of the original tube, while the unfinned end portion will remain at the original diameter and wall thickness with the metal thereof in its original soft unwork-hardened condition.

The finned tubing produced by my improved method may have the fins thereof of any desired height in comparison with the diameter of the original tube. In the product shown in connection with Fig. 3, the fins G' are no greater in height than the original diameter of the tube G. On the other hand, in the product shown in Fig. 5 the fins H' are of considerably greater diameter than that of the original tube H.

What I claim as my invention is:

1. The method of forming a length of tubing with an integral helically extending fin which

comprises subjecting a length of tubing to a circumferential rolling pressure applied in a radially inward direction on axially spaced helically aligned peripheral portions of progressively increasing axial extent and spaced apart progressively decreasing distances, extruding material from the tubing wall in a radially outward direction between the axially spaced peripheral portions by the radially outward opposing force resulting from the radially inward rolling pressure applied to the wall of the tubing, and at the same time primarily guiding the extruded material to form a helically extending fin.

2. The method of forming a length of tubing with an integral helically extending fin which comprises applying a circumferential rolling pressure to a length of tubing in a generally radially inward direction against axially spaced substantially helically aligned peripheral portions, and transmitting the radially inwardly directed pressure into a primary resultant pressure acting in a generally radially outward direction to displace material from the wall of the tubing radially outwardly between the axially spaced peripheral portions to form a helically extending fin.

3. The method set forth in claim 2 in which the length of tubing is reduced in diameter and elongated in the direction of advancement of the tube by the application of the rolling pressure on the wall of tubing.

4. The method of forming from tubular stock a length of tubing with an integral helically extending fin and with an unfinned portion having a diameter at least as great as the diameter of the fin and approximating the diameter of the stock, comprising applying a circumferential rolling pressure to the length of tubular stock in a radially inward direction against axially spaced helically aligned peripheral portions of progressively increasing axial extent, transmitting the radially inwardly directed pressure into a primary resultant pressure acting in a generally radially outward direction to displace material from the wall of the tubular stock radially out-

wardly between the axially spaced peripheral portions to form a helically extending fin, reducing the stock by the pressure of the fin rolling operation an amount approximating the height of the fin, and forming a cylindrical unfinned portion of the length of tubing by relieving the fin rolling pressure.

5. The method of forming a length of tubing with an integral helically extending fin which comprises initially reducing the diameter of the length of tubing by applying a circumferential rolling pressure on the wall of the tubing and thereafter further reducing the diameter of the tubing by applying a circumferential rolling pressure in a radially inward direction against axially spaced helically aligned peripheral portions of progressively increasing axial extent, and transmitting the radially inwardly directed pressure into a primary resultant pressure acting in a generally radially outward direction to displace material from the wall of the tubing radially outwardly between the axially spaced peripheral portions to form a helically extending fin on the reduced length of tubing.
